CLAIM

The ornamental design for a vehicle sign, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, right perspective view of a first embodiment of a vehicle sign showing our new design;

FIG. 2 is a front view thereof;

FIG. 3 is an enlarged front view of the front, bottom, center portion of FIG. 2;

FIG. 4 is a top, front, right perspective view of a second embodiment of a vehicle sign;

FIG. 5 is a front view thereof; and,

FIG. 6 is an enlarged front view of the front, bottom, center portion of FIG. 5.

The broken lines immediately adjacent to the shaded area represent the bounds of the claimed design. All other broken lines show environment and form no part of the claimed design. The stippling shown in FIGS. 1-3 depicts a contrast in appearance.
